UNITED STATES PATENT OFFICE.

WILLIAM W. BLAKELY, OF DETROIT, MICHIGAN.

LEAF-SPRING COMPRESSOR.

1,425,832.

Specification of Letters Patent. Patented Aug. 15, 1922.

Application filed December 27, 1919. Serial No. 347,856.

To all whom it may concern:

Be it known that I, WILLIAM W. BLAKELY, a citizen of the United States of America, residing at Detroit, in the county of Wayne 5 and State of Michigan, have invented certain new and useful Improvements in Leaf-Spring Compressors, of which the following is a specification, reference being had therein to the accompanying drawings.

10 This invention relates to leaf spring compressors and its object is to provide an attachment for a vehicle leaf spring to hold said spring under sufficient compression during shipment of the vehicle to prevent activity of the spring during shipment due to 15 movement of the conveyance in which the vehicle is being shipped.

A further object is to provide a leaf spring compressor that may be very quickly attached to and detached from the vehicle spring and which will be positively restrained against any tendency to escape from the spring due to the expansive force of the latter and to such stresses as may 25 arise during shipment.

In the drawings:

Figure 1 is a perspective view of the invention;

Figure 2 is a view in side elevation of a 30 semi-elliptic vehicle spring to which the invention is applied;

Figure 3 is a view similar to Figure 2 but showing the invention applied to a spring of the cantilever type.

35 In the construction shown in Figures 1 and 2, the reference characters A and B respectively designate two pivotally connected wire loops, the loop A being of a size adapting it to be slipped over a sill C and over a 40 supporting vehicle leaf spring D while said spring is temporarily subjected to any suitable force placing it under compression, and of sufficient strength to maintain the compression of the spring when relieved of said 45 force. The loop B is proportioned to loosely embrace the spring D and forms an anchorage member to restrain the loop A against shifting toward the convergent ends of the 50 sill and spring. This result the loop B 55 accomplishes by engaging any suitably located projection on the vehicle, as for example, one of the clip bolts E, which attach the spring to the axle F. Pivotal connection between the two loops A and B is preferably established by forming pairs of eyes G at the adjacent ends of the two loops and

engaging said eyes by a bolt G'. Preferably, the loop A is of a length that will permit it to assume an inclined position when engaging the compressed spring D so 60 that, if by any sudden shock, said spring is subjected to a greater compression during shipment than that originally imposed thereon, said loop will tend to swing about its lower end so as to maintain the increased 65 compression rather than to release any of the original compression.

To engage the loop B with the spring, said loop is detached from the loop A and its ends are sprung apart sufficiently to pass 70 at each side of the spring.

Referring now to the arrangement shown in Figure 3, H is a cantilever spring supporting a sill I, and attached at its reduced end by clip bolts J to an axle K, having the 75 underlying truss rod L. In applying the invention to such a construction, the loop B is bent at a right angle, so that it may be hooked over the truss rod L after the spring H has been sufficiently stressed to allow the 80 loop A to establish a tie between the sill I and the reduced end of said spring as Figure 3 clearly illustrates. In this instance there is no necessity for detaching the loops A and B from each other.

85

What I claim as my invention is:

1. A leaf spring compressor comprising a tie member and an anchorage member pivotally attached to said tie member, said members being respectively adapted for 90 quick detachable engagement with a vehicle spring and a relatively fixed portion of a vehicle.

2. A leaf spring compressor comprising a tie member forming a substantially closed 95 loop proportioned to embrace a vehicle leaf spring and a sill of the vehicle, and an anchorage member attached to said tie member for maintaining its engagement with said spring and sill.

100

3. A leaf spring compressor comprising a tie member forming a substantially closed loop proportioned to embrace a vehicle leaf spring and sill supported by said spring, and an anchorage member adjustably engaged with one end of said tie member.

4. A leaf spring compressor comprising a tie member engageable with a sill and a supporting leaf spring of a vehicle to maintain compression of said spring, and a 110 looped anchorage member pivotally connected to said tie member and engageable

with a part of the vehicle to maintain the desired position of the tie member.

5. A leaf spring compressor comprising a tie member, engageable with a sill and a leaf spring supporting said sill to maintain said spring under compression, and an anchorage member pivotally attached to said tie member hooked for engagement with a part of the vehicle.

10 6. A leaf spring compressor comprising a pair of looped members one of which is proportioned to embrace a vehicle sill and a leaf spring supporting said sill to maintain the spring under compression, the other being proportioned to loosely engage the spring; the extremities of said members forming coaxial eyes, and a bolt engaging said eyes to establish a pivotal connection between said looped members.

20 7. A vehicle leaf spring compressor comprising a tie member looped to embrace a leaf spring, and means carried by the tie member for positively restraining the same from shifting longitudinally of the spring.

25 8. In a leaf spring compressor comprising a pair of pivotally connected loop members, one of which forms a tie member, and the

other an anchorage member, said members being adapted by their loop for quick detachable engagement respectively with a vehicle spring and a relatively fixed portion of a vehicle.

9. A leaf spring compressor comprising a tie member having a terminal shoulder for respectively engaging a vehicle spring and a sill of a vehicle, and an anchorage member pivotally secured to one end of said tie member.

10. A leaf spring compressor comprising a pair of pivotally connected loop members, one of which is proportioned to embrace a vehicle sill and a leaf spring supporting said sill, to maintain the spring in compression, the other being to loosely engage the spring and constituting an anchorage member.

11. The combination with a vehicle spring and means mounting the same permanently upon an axle, of a compressor for said spring comprising a tie member, and an anchorage member pivotally attached to said tie member.

In testimony whereof I affix my signature.

WM. W. BLAKELY.
